UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A BRUSH OR MIRROR BACK.

SPECIFICATION forming part of Design No. 19,062, dated April 30, 1889.

Application filed March 20, 1889. Serial No. 304,047. Term of patent 7 years.

To all whom it may concern:

Be it known that I, HENRY BERRY, a citizen of the United States, residing at Shelton, in the county of Fairfield and State of Connecticut, have invented and produced a certain new and original Design for Brush or Mirror Backs, of which the following is a specification, reference being had to the accompanying drawing, forming a part thereof, and which shows a plan view of a brush or mirror back shaped and ornamented in accordance with my design.

The leading features of my design are the outline of the back, the same being formed largest at or near the upper end thereof and smallest at the end to which the handle is adapted to be attached, and the floral ornamentation appearing upon the surface thereof.

A is the rear face of the back, in the reverse face of which the brush or mirror is adapted to be inserted. This back is broader at its upper end, *a*, than at its lower end, *b*, which is quite narrow where the handle is adapted to be attached. A border or margin, *c*, extends around the edge of the surface of the back, forming a sort of panel. Upon this

panel, which is inclosed by said margin, appears a floral and foliate ornamentation, the details of which are the representation of the rose *d* and leaves *e* near the upper end of the panel, the chrysanthemum-blossom *f* and leaves *g* by the side of the rose, the representation of a rose-bud, *h*, below the chrysanthemum-blossom, a second chrysanthemum-blossom, *j*, beneath the rose *d*, and the leaves *k* and forget-me-not blossoms *m* below and to the right of the representation of the chrysanthemum-blossom *j*. The lower end of the back, where the handle is joined thereto, is finished by a trifoliate figure, *n*, which extends onto the surface of the panel from the bottom and sides thereof.

I claim—

The design for a brush or mirror back of the shape and having surface ornamentation substantially as herein shown and described.

In testimony whereof I affix my signature in presence of two witnesses.

HENRY BERRY.
